WHEEL

Harry M. Pflager, St. Louis, Mo., assignor to
 General Steel Castings Corporation, Granite
 City, Ill., a corporation of Delaware

Application February 10, 1933, Serial No. 656,075

7 Claims. (Cl. 295—27)

This invention relates to vehicle load-sustaining wheels, and particularly to wheels for railway cars and locomotive drivers.

In order to afford rigidity to spoke-type wheels for railway vehicles in particular, it has been customary to form the spokes of substantial solid section, of box or other hollow section, with cored openings, or of channel section. Where the wheel is formed of cast metal, solid spokes are subjected to substantial shrinkage strains during cooling in the mold, which cause casting difficulties. Spokes of channel, box or other hollow section require the use of cores which increase the cost of manufacture and make cleaning of the casting a difficult and expensive proposition. Also, in the latter case it is difficult to discover defects in the metal since all surfaces are not exposed.

An important object of the present invention is to provide an improved and simplified vehicle wheel which may be cast in a green sand mold without the use of cores.

Another object is to produce a cast wheel structure with all surfaces exposed so that the casting can be easily inspected and any defects readily discovered.

Another object is to provide a wheel structure utilizing a minimum of metal in the spokes without loss of necessary rigidity and resistance to lateral forces.

Another object is to equalize shrinkage stresses between the spokes and heavier connected parts by gradually thickening the spokes towards their connections with the hub and rim.

Another object is to provide a cast wheel which may be cheaply and readily cleaned.

Still another object is to produce a wheel center structure free of internal pockets for accumulation of dirt, rock, ballast, and other foreign substances.

These objects and others are attained substantially by the structures in the accompanying drawings, in which—

Figure 1 is a side view of a locomotive driver center illustrating one form of the invention.

Figures 2, 3, 5, and 6 are sectional views taken on the corresponding section lines of Figure 1.

Figure 4 is a sectional view through the mold for forming the cast wheel structure and showing the wheel in section substantially on the line 4—4 of Figure 1.

Figure 7 is a side view of a car wheel utilizing the invention.

Figures 8, 9 and 10 are sections taken on the corresponding section lines of Figure 7.

Figure 11 is a half side view of a car wheel illustrating a modification.

Figure 12 is a transverse section taken through the center of the wheel in Figure 11.

Figure 13 is a fragmentary view of a mold 5 similar to Figure 4 and showing a section of a modified form of spoke having the transverse web slightly inclined.

In Figures 1 to 6 is shown a locomotive driver wheel center structure formed of an integral 10 casting comprising rim 1 having an enlarged counterbalance portion 2 with pockets 3 for adjusting the weight of the counterbalance. At the center is the hub 4 for receiving the axle, and having a lateral enlargement 5 perforated 15 for receiving a driving or connecting pin. The rim and hub are connected by a series of Z-shape spokes indicated generally at 6 and 6a.

The spokes 6 are Z-shaped in section, each including a web portion 7 disposed transversely to the plane of the wheel, and outer and inner flanges 8 and 9 substantially paralleling the plane of the wheel and spaced from each other transversely of this plane. The corresponding flanges 8 and 9 of adjacent spokes extend towards each other from webs 7 and merge adjacent the hub as at 10 and 11, and adjacent the rim as at 12 and 13. These flanges, together with merged portions 10, 11, 12, and 13, constitute, in effect, flat, tapering, spoke-like webs disposed alternately 30 on opposite sides of the wheel and with central openings 14 and 15, these openings being reinforced by ribs or beads 16 and 17. On the inside of the wheel, the central hub is enlarged at 18 to form a hub face for engaging the driving 35 box. The openings 14 between flanges 8 on the outside of the wheel extend from the inner edge of the rim to the edge of the outer part of the hub 4, and the openings 15 between the inner flanges 9 extend to the edge of the widened inner 40 hub face 18. In order to further strengthen the wheel, any or all of the openings 14 and 15 may be omitted.

Extending between the rim 1 and the pin bearing portion 5 of the hub is a broad spoke 6a 45 formed of a pair of Z's with their top flanges merged in a web 19 braced at the center by a radial rib. Transversely disposed flanges 20 connect the edges of web 19 and flanges 21, the latter being in the plane of and merging with the inner 50 flange parts 9 of the adjacent Z-shaped spokes. The flanges 21 are reinforced by beads 22 merging with beads 16 on the adjacent flanges 9, and the web 19 is braced at the center by a radial rib 23. This enlarged spoke 6a is for the pur- 55

pose of bracing the bearing 5 which receives connecting or driving rod forces. Web 19 is perforated at 24 to lighten the structure.

The rim 1 is of comparatively thin section and 5 is braced by the web 19 and by merged portions 12 and 13 of the spoke flanges 8 and 9, these merged portions being positioned alternately near the outer and inner edges of the rim, respectively. As shown in Figure 6, the portions of the rim between the spokes are braced radially by a web 10 such as 13.

All of the webs and flanges forming the various 15 spokes are relatively thin at the center and gradually increase in thickness in merging with the rim and hub. With reference to Figure 2, it will be seen that the flanges 8 and 9 of the spokes 6 gradually increase in thickness from the center outwardly and inwardly and merge with the rim 1 and hub 4 at their points of greatest thickness. With reference to Figure 1, it will be seen 20 that the transverse webs 1 and flanges 20 similarly increase gradually in thickness from the center towards the rim and hub. This gradual tapering of the spoke webs and flanges has the 25 effect of equalizing shrinkage stresses between the spokes, rim and hub set up during solidification of the metal, by providing a gradual gradation in mass of the metal at the joints, instead of the sharp variation which would occur if uniformly 30 thin webs and flanges merged directly with the heavier rim and hub.

In Figure 4 is shown a section through the mold in which the wheel center is cast and including the usual cope 26 and drag 27 rammed with 35 green sand 28 and clamped together. It will be seen that alternating portions of the cope and drag project into the openings between transverse webs 7 and into openings 14 and 15 between the spoke flanges, thus avoiding the use of cores.

40 In Figure 7 is shown a wheel for car or engine trucks, the tire 29 being cast integral. All of the spokes 30 are Z-shaped in section, as are the spokes 6 in Figure 1, and the transverse webs 31 and outer and inner flanges 32 and 33, respectively, gradually increase in thickness from the center in merging with the rim 34 and hub 35. This wheel is formed similarly to that in the previous form and attains the same general advantages.

50 In Figures 11 and 12 is shown a car wheel illustrating a somewhat modified form of spoke. The wheel includes integrally formed tire 36, rim 37, hub 38 and spokes generally indicated at 39. Each spoke is formed of a triangular web 40 disposed transversely of the plane of the wheel and outer and inner flanges 41 and 42, respectively. The corresponding flanges of adjacent spokes merge at 43 and 44 near the edge of the hub. Flanges 41 and 42 follow the edges of triangular 55 webs 40 and are, accordingly, substantially spaced apart at the hub end of the spokes and merge at 46 in a continuous line at the intersection of the spokes with the rim. Diagonal ribs 45 are provided at intervals around the wheel to reinforce the outer extremities of the spokes, these ribs constituting extensions of the web parts 40. This type of construction utilizes less metal than that in the previous forms and is especially advantageous where the wheel is not subjected to unusually heavy lateral forces.

60 In Figure 13 is shown a sectional portion of a mold for a wheel having spokes with a transverse web 47 which is inclined so as to facilitate the drawing of the pattern from the mold.

70 75 The novel disposition of the various elements

adapts the wheel to be readily formed by the most economical casting procedure, while at the same time affording maximum rigidity to the rim and maximum strength to resist lateral forces with a minimum of weight. The surfaces of the 5 castings above described can be readily cleaned, finished and inspected.

While in certain of the figures is shown a thick tire with the flange integral, the rim can be made thinner to receive any form of tire. Various features of the invention may be advantageously used in vehicles other than railway locomotives and cars, and particularly, where a comparatively light wheel of great strength is required. The invention is not limited to the exact 10 details shown, and these may be modified in various respects without departing from the spirit of the invention. The exclusive use of all such modifications as come within the scope of the 15 appended claims is contemplated.

20 I claim:

1. A vehicle wheel structure comprising hub and rim parts and connecting spokes of Z-shaped cross-section with flanges spaced transversely of the plane of the wheel, corresponding flanges of 25 adjacent spokes extending towards each other and merging with each other and with said rim part adjacent one edge thereof whereby both edges of said rim part are reinforced at alternate intervals around the structure by substantial portions of said merging flanges.

2. A vehicle wheel center comprising hub and rim parts and structure connecting said parts including webs disposed transversely to the plane of the wheel, and flanges projecting substantially 35 perpendicularly from said webs and merging with each other, alternate ones of said flanges being spaced transversely of the plane of the wheel from the intervening ones, there being substantial openings between the merging flanges whereby all 40 of said webs and flanges co-operate to form Z-shaped spokes.

3. A cast metal railway vehicle wheel center structure adapted to be molded without cores and comprising continuous hub and rim parts and 45 Z-section spokes connecting the same, said spokes having their webs disposed transversely to the general plane of the wheel structure and corresponding flanges of adjacent spokes extending towards and merging with each other and reinforcing alternate outer edge portions of said hub and rim parts, all of the spoke webs and flanges being relatively thin at their mid-points and uniformly increasing in thickness from said points to said hub and rim parts.

4. In a railway vehicle wheel of cast metal, a hub, a rim, and a spoke of Z-shape cross-section between said hub and rim, said hub, rim, and spoke being formed integrally with each other with the web of said spoke extending transversely of the plane of the wheel and with the flanges of said spoke extending parallel to the plane of the wheel and substantially merging respectively with the corresponding faces of said hub and rim which are parallel to the plane of the wheel.

5. A locomotive driving wheel center of cast metal comprising a hub, a rim, a counterbalance, and a spoke of Z-shape cross-section between said hub and counterbalance, said hub, rim, spoke, and counterbalance being formed integrally with the web of said spoke extending transversely of the plane of the wheel and with the flanges of said spoke extending parallel to the plane of the wheel and substantially merging respectively with 70 75 the corresponding faces of said hub and rim which are parallel to the plane of the wheel.

the corresponding faces of said hub and counterbalance.

6. A locomotive driving wheel center of cast metal comprising a hub, a rim, a counterbalance, and a plurality of spokes of Z-shape cross-section between said hub and counterbalance, said hub, rim, spokes and counterbalance being formed integrally, with the webs of said spokes extending transversely of the plane of the wheel and with 10 the flanges of said spokes extending parallel to the plane of the wheel and substantially merging respectively with the corresponding faces of said hub and counterbalance which extend parallel to the plane of the wheel, at least one pair of 15 flanges on adjacent spokes facing towards each other and merging with each other intermediate said hub and counterbalance.

7. In a railway vehicle wheel of cast metal, a hub, a rim, and a plurality of spokes of Z-shape cross-section between said hub and rim, said hub, rim, and spokes being formed integrally with each other with the webs of said spokes extending 5 transversely of the plane of the wheel and with the flanges of said spokes extending parallel to the plane of the wheel and substantially merging respectively with the corresponding faces of said hub and rim which extend parallel to the plane 10 of the wheel, at least one pair of flanges on adjacent spokes facing towards each other and merging with each other intermediate said hub and rim. 15
